CLAIM

The ornamental design for a water distributor for a snow production cannon, as shown and described.

DESCRIPTION

FIG. 1 is a perspective view of a water distributor for a snow production cannon, showing my new design;

FIG. 2 is a side elevational view thereof;

FIG. 3 is a side elevational view thereof from the left of FIG. 2;

FIG. 4 is a side elevational view thereof from the side opposite that shown in FIG. 2;

FIG. 5 is a side elevational view thereof from the left of FIG. 4;

FIG. 6 is a top plan view thereof;

FIG. 7 is a bottom plan view thereof; and,

FIG. 8 is a view similar to FIG. 2, but with a filter unit contained therein partially extended.

FIG. 1

FIG. 2

FIG. 3

FIG. 4

FIG. 5

FIG. 6
